ABSTRACT OF THE DISCLOSURE

The invention is a modulation, demodulation, and decision making process for binary data transmission called Coherent Echo Modulation and Detection. The essential features of the invention are that the last n data bits transmitted (n is an integer, e.g., $n=100$) are used to modulate one of n orthogonal subcarriers or signals and then each modulated subcarrier is again modulated by the next bit to be transmitted. All n doubly modulated subcarriers are then transmitted, doubly demodulated, and the noisy measurements of the modulating data are retained and accumulated in properly weighted sums. These properly weighted sums determine current decisions as to what the last n data bits transmitted were, and these decisions determine a reference used in the demodulating process. After n bit periods following the initial transmission of a data bit, a final decision is made on that data bit, the weighted sum of measurements determining that final decision is discarded, and the bit no longer enters into the modulation, demodulation, and decision-making process. The full advantages are acquired gradually during the transmission of the first n data bits.

This invention relates generally to a system for transmitting binary data.

Various communication systems exist which enable binary data to be transmitted between two or more remote stations. The characteristics of such systems can differ considerably, thus making each particularly suitable for a certain type environment. Thus, for example, a particular system may be best suited for a low noise narrow bandwidth environment while another system may be more appropriate in the presence of a high noise level where a wide bandwidth is acceptable.

As an example, multiple access communication systems are known in the prior art which do not use frequency or time division multiplexing, but rather employ an independently generated pseudo-random (PR) sequence in an attempt to make the interference due to other subscribers appear as white noise. Such a PR sequence is commonly generated synchronously at both the transmitter and receiver. At the transmitter, it is used to select or determine pseudo-randomly the signal to carry each bit of data. At the receiver, it is used to define a reference signal so that efficient signal detection can be maintained.

A data transmission system is referred to as a stored reference system if the reference signal is generated at the receiver, and as a transmitted reference system if both the reference signal and the data carrying signal are transmitted. Generally, stored reference systems have significant synchronization or acquisition problems. These problems are for the most part avoided in the transmitted reference system where the current reference is transmitted, but only at the expense of signal power and bandwidth.

The present invention is directed to an improved communication system in which the future, rather than the

2

current, reference is transmitted. The future reference is a known function of the previously transmitted data and a starting reference or address data. As a consequence, only bit synchronization is required and neither additional signal power nor additional bandwidth are required for transmitting the reference. Synchronization acquisition is facilitated to an extent comparable to that of the transmitted (current) reference system but without the signal power and bandwidth penalties.

10 The invention furthermore provides for significant transmitter power savings compared to the stored reference system which savings are a consequence of two factors. Initially, as a consequence of doubly modulating, or in general m -fold modulating, the transmitted signal, 15 power savings of 50% and more are realized in the case where there is no signal fading and the only interference is additive white gaussian noise. Secondly, by inherently providing both a time and frequency diversity, the invention provides a significant immunity to signal fading and 20 to non-white and burst-type additive noise. Since this type of signal interference is commonly overcome by increasing the transmitted signal power, the immunity permits or is worth even further transmitter power savings.

25 A consequence of the transmitter power saving capabilities of the invention is that, when used in a multiple access system where a number of users transmit over a frequency band without time or frequency restriction, a 30 significantly improved utilization of the frequency band is possible, e.g. the number of users accommodated could be increased by a factor of two or more.

Briefly, an embodiment of the present invention includes means for modulating signal energy in accordance 35 with binary data to be transmitted together with means for demodulating signal energy at the receiver to recover the binary data. In essence, the system contemplates that the last n data bits transmitted (n is an integer, e.g. 100) are each used to modulate one of n subcarriers or 40 signals (which signals are preferably orthogonal to one another) and then all of the modulated subcarriers are again modulated by the next bit to be transmitted. All n doubly modulated subcarriers are then transmitted, doubly 45 demodulated, and the noisy measurements of the modulating data are retained and accumulated in properly weighted sums. These properly weighted sums are used to determine current decisions as to what the last n data bits transmitted were, and these decisions are used to 50 determine a sequence of reference bits which are used in the demodulating process. After n bit periods following the initial transmission of a data bit, a final decision is made on that data bit.

In addition to an embodiment in which each subcarrier is doubly modulated (hereinafter referred to as a two-fold system), the invention also contemplates more complex m -fold systems.

The novel features that are considered characteristic 60 of this invention are set forth with particularity in the appended claims. The invention will best be understood from the following description when read in connection with the accompanying drawings, in which:

FIG. 1 is a block diagram generally illustrating two users communicating with one another employing a system in accordance with the present invention;

FIG. 2 is a block diagram of a transmitter which can be employed in the implementation of a two-fold system in accordance with the present invention;

FIG. 3 illustrates a typical binary sequence and shows 70 the manner in which the elements of FIG. 2 are controlled to transmit such a sequence;

FIG. 4 is a block diagram of a receiver which can be employed in the implementation of a two-fold system in accordance with the present invention;

FIG. 5 is a block diagram of a transmitter which can be employed in the implementation of a three-fold system in accordance with the present invention; and

FIG. 6 is a block diagram of a receiver which can be employed in the implementation of a three-fold system in accordance with the present invention.

Attention is now called to FIG. 1 of the drawings which generally illustrates a pair of user stations 10 and 12, each adapted to transmit binary data to and receive binary data from the other station. Each station includes a transmitter section 14 and a receiver section 16.

Attention is now called to FIG. 2 which illustrates the details of a transmitter section 14 in accordance with one embodiment of the invention. Briefly, the transmitter section of FIG. 2 is based on the concept that each of a sequence of data bits (i.e. binary digits) will be used during $n+1$ bit periods to modulate the signals provided by n signal generators. More particularly, in the embodiment of FIG. 2, during each successive bit period, each of the n signal generators is modulated by the most recently provided data bit and by one of the n previously provided data bits.

Thus, the transmitter section depicted by FIG. 2 includes a data bit source 18 which provides a sequence of data bits intended to be transmitted. The output of the data bit source is connected to the input of binary stage X_0 of a shift register 20. The shift register 20 includes $n+1$ binary stages, and accordingly in addition to stage X_0 , includes stages X_1-X_n . Various shift register implementations are known in the prior art and suffice it to say that in response to the application of a shift pulse on terminal 22 by a timing means 24, the state of each of the shift register stages will be shifted to the right one stage. Information shifted out of stage X_n will be discarded.

In accordance with the present invention, the output of each of stages X_1-X_n is connected to the input of a different one of n gates G_1-G_n . In addition, the output of binary stage X_0 is connected to the input of all of the gates G_1-G_n . The output from each of the gates is connected to the input of a different one of n signal generators S_1-S_n . The signal generators are controlled by timing means 24 via conductor 26.

Thus, in the operation of the transmitter section of FIG. 2, the data bit source 18 will provide a data bit to stage X_0 during each bit period defined by timing means 24 via conductor 28. Thus, during each bit period, each of the gates will be controlled in accordance with a particular one of the n previously provided data bits and the most recently provided data bit stored in stage X_0 . As noted, since each gate modulates a different one of the signal generators, the signals provided thereby will each be modulated in accordance with the most recently provided data bit and one of the n previously provided data bits. In this manner, each data bit is effectively transmitted during $n+1$ bit periods.

In order to better understand the operation of the transmitter section of FIG. 2, attention is called to FIG. 3 which depicts an arbitrary sequence of data bits arranged such that the earliest occurring data bit is illustrated toward the right and the subsequently occurring data bits are illustrated in successive positions extending therefrom toward the left. Let it be assumed that the value of n referred to in FIG. 2 is equal to five. Also, let it be assumed that the five bracketed data bits in the data bit sequence illustrated in FIG. 3 comprise the n previously submitted data bits and that the circled data bit comprises the bit most recently provided by the data bit source 18. It should also be noted that the sequence of data bits is illustrated as being comprised of "+1's" and "-1's". The gates G_1-G_n illustrated in FIG. 2 are assumed to be exclusive-Or

gates so that they provide a true or positive output when the inputs thereto are alike and a false or negative output when the inputs thereto are not alike. In this manner, the gates G_1-G_n can generate the arithmetic product of the data bits. In other words, if the two inputs to one of the gates are both "-1's", the gate will provide a positive or "+1" output. Similarly, if the two inputs are both "+1's", the gate will still provide a positive output. On the other hand, if one input to a gate is "-1" and the other is "+1", then the gate will provide a negative or "-1" output.

With the foregoing comments in mind, consider the states of binary stages X_0-X_5 during a bit period T_1 in which the circled data bit has just been stored in stage X_0 . With the content of the stages X_0-X_5 as illustrated in FIG. 3, the signals provided by the generators S_1-S_5 will be modulated as represented. It should be recalled that all of the signal generators S_1-S_n provide unique signals which, as will be explained in greater detail hereinafter, are preferably orthogonal to one another.

During the subsequent data bit period, T_{1+1} , the content of each of stages X_0-X_4 is shifted one stage to the right as illustrated as a new data bit (+1) is brought into stage X_0 . Likewise, during each of the succeeding bit periods, a new data bit will be brought into the stage X_0 and the state of each of the other stages will be shifted to the right. Of course, each shifting operation involves the discarding of the previous content of stage X_5 . As should now be understood from the tabular format of FIG. 3, the signal generators S_1-S_5 will each be modulated by a unique one of the n previous data bits together with the most recently provided data bit. Mathematically, the modulated signal provided by any one of the signal generators can be expressed as

$$S_{im} = X_1 \cdot X_0 \cdot S_i$$

where i represents any number between 1 and n .

Attention is now called to FIG. 4 of the drawings which illustrates a receiver section 16 adapted to receive a composite signal having components $S_{1m}, S_{2m} \dots S_{im} \dots S_{nm}$ and in response thereto, to recreate the data bit sequence provided by the data bit source 18 at the transmitter. The receiver section operates upon the concept of developing a sequence of reference data bits which are stored in reference storage stages $X_{1R}-X_{nR}$. Each of the reference data bits, e.g. X_{1R} , is initially combined with the corresponding received signal component to recover the transmitted bit X_0 . Thus, n initial manifestations, each intended to represent X_0 , are recovered and these are summed to develop a weight indicating the most likely value of X_0 , i.e. +1 or -1. This value is then stored in a most recent digit storage stage X_{0R} and is used to recover n correction manifestations each intended to represent a different one of the n preceding bits. These correction manifestations are utilized to correct the sequence of reference bits.

More particularly, the receiver section of FIG. 4 is comprised of a set of n correlators $C_1 \dots C_1 \dots C_n$. The composite signal received from the transmitter which is of course comprised of n modulated signal components, is provided to the input of each of the correlators via conductor 40. A different locally generated signal is provided to each of the correlators, each signal corresponding to the unmodulated signal provided by one of the signal generators of the transmitter section. Thus, a signal S_{2R} corresponding to the unmodulated signal provided by signal generator S_2 of FIG. 2, is provided to correlator C_2 of FIG. 4. Accordingly each of the correlators will provide an output signal which is generally represented by the equation

$$W_i = K X_1 X_0 + Y_i$$

where K represents a transmission attenuation factor and Y_i represents noise introduced on the i channel. Cor-

relators suitable for isolating the respective signal components are readily known in the art and will not be considered in detail here. The output of each of these correlators is initially fed to a first multiplier 42 which multiplies the signal W_1 by a corresponding reference bit stored by previously mentioned stage X_{1R} . As a consequence, multiplier 42 will provide an output signal

$$W_1 X_{1R} = K X_1 X_{1R} X_0 + Y_1 X_{1R}$$

Let it be assumed that the noise level term $Y_1 X_{1R}$ is not very great. Accordingly, the term $K X_1 X_{1R} X_0$ should be equal to $K X_0$ whenever the reference bit X_{1R} does in fact correspond to its transmitted counterpart X_1 . Therefore, the multiplier 42 in each of the n channels of the receiver section of FIG. 4 should provide an initial manifestation representing the state of the last data bit X_0 . These manifestations provided by all of the multipliers 42 are coupled to the input of a summing network 44 which determines whether more multipliers 42 indicate that the bit X_0 is -1 or $+1$. If it is assumed that the noise level is sufficiently low that at least half of the channels will provide a correct indication, then the summing network should indicate the proper value of the transmitted bit X_0 . The sum developed by the summing network 44 is stored in a most recent digit accumulating means A_0 which can comprise either an analog or digital store. The sum or weight stored in the accumulating means A_0 provides an indication of the reliability of the decision made with respect to X_0 . That is, if all of the channels indicated the value of X_0 to be the same, e.g. $+1$ (assuming $K=1$), then the accumulating means A_0 would store a unanimous decision, e.g. $+n$. On the other hand, if all of the channels indicated that the bit X_0 was -1 , then the accumulating means A_0 would again indicate a unanimous decision, e.g. $-n$. On the other hand, if about half the channels indicated the bit X_0 was $+1$ and about half indicated the bit X_0 was -1 , then a value close to zero would be stored in the accumulating means A_0 indicating a low reliability for the decision with respect to the bit X_0 . In any event, the accumulating means A_0 controls the state of the most recent digit storage stage X_{0R} . That is, if the sum stored in the accumulating means A_0 is positive, then a $+1$ will be stored in the storage stage X_{0R} and if the sum is negative, then a -1 will be stored in the stage X_{0R} .

Prior to the receipt of a subsequent data bit, the sum stored in the accumulating means A_0 is shifted into accumulating means A_1 . The accumulating means A_1 determines the state of stage X_{1R} in the same manner as the accumulating means A_0 determined the state of the stage X_{0R} . However, prior to shifting the sum from one to the next accumulating means, the sum in each accumulating means is corrected by employing the newly determined most recent data bit stored in stage X_{0R} to correct the other n reference data bits stored in the stages $X_{1R} \dots X_{nR} \dots X_{nR}$.

In order to do this, the output of the stage X_{0R} is coupled to the input of a multiplier 46 in each of the n channels. A different correlator is connected through a delay means 48 to each of the multipliers 46. The delay means 48 are employed to permit the multipliers 42 to initially determine the value of X_{0R} prior to it being used by multipliers 46. The multipliers 46 will provide an output signal

$$W_1 X_{0R} = K X_1 X_0 X_{0R} + Y_1 X_{0R}$$

If the most recent digit X_{0R} was properly determined, then the product $X_0 X_{0R}$ will be equal to $+1$ and the signal provided by each of the multipliers 46 will properly indicate the value of one of the n previous data bits. Thus the output of each multiplier 46 constitutes a correction manifestation which is added to the weight or sum carried by the corresponding accumulating means

tending to correct or increase the reliability of the weight stored therein. It will be recalled that the magnitude of the sum carried by the accumulating means can be considered to represent the reliability of the decision made with respect to the corresponding reference data bit.

Accordingly, from the foregoing explanation of the operation of the receiver section of FIG. 4, it should be appreciated that $2 \cdot n$ separate correlation measurements are made with respect to each received data bit, i.e. n initial manifestations are made simultaneously by the n channels when the data bit first appears to establish the initial weight in the accumulating means A_0 and the initial state of the stage X_{0R} . As the weight is successively thereafter shifted through the accumulating means during the n subsequent data periods, it is successively modified by n sequential correction manifestations which in the absence of significant noise, will tend to increase the reliability of the decision as to the identity of the data bit. A final decision with respect to the identity of a data bit is not made until the bit has been effectively shifted through $n+1$ reference storage stages $X_{0R} \dots X_{nR}$.

It is important to realize that the aforescribed system incorporates inherent time and frequency diversity which significantly improves the likelihood that the data bits will be properly recovered. The system inherently incorporates time diversity in that each data bit is effectively transmitted over $n+1$ data bit periods and as a consequence, a burst of noise in one or more of these $n+1$ periods will not cause a complete loss of that data bit since it can very likely be properly ascertained from its transmission during other bit periods. The frequency diversity arises from the fact that each of the data bits will modulate each of the n signal generators. If the n signal generators generate orthogonal signals, and n is large, then necessarily the bandwidth utilized to transmit the data is large (of the order of n) relative to that normally required to transmit the data. The inherent frequency diversity is implied by the use of this extra large bandwidth and the fact that the full bandwidth is utilized in transmitting each data bit since each bit modulates each signal at least twice. Thus, the bandwidth utilized in transmitting the data is fully utilized in the transmission of each data bit. Accordingly, even though noise may exist throughout a small portion of a wide frequency band, this should not prevent the data bit from being recovered throughout the remaining less noisy portions of the band.

Thus far, little has been said with respect to the particular signals provided by the signal generators $S_1 \dots S_n$ of FIG. 2. Preferably, the signals should comprise a set of signals (functions) which are orthogonal to one another. Orthogonal signal generator ensembles are readily known in the art. One example is suggested by a typical pseudo-random signal. This ensemble is constructed using a sinusoidal carrier, dividing the bit period into n equal disjoint subintervals, and defining the j th signal to coincide with the sinusoidal carrier during the j th subinterval and to be zero outside the subinterval for $j=1, 2 \dots n$. Another simple example is an ensemble consisting of n sinusoidal carriers with the j th signal set equal to the j th carrier over the entire bit interval and set to zero outside this interval for $j=1, 2 \dots n$. The carriers could be easily selected to be orthogonal over the bit period. Another example is a mixture of the first two. If n can be written as the product pq with p and q both integers, then the bit interval can be divided into q equal disjoint subintervals and p carriers can be selected so that each carrier can be used to define q orthogonal signals (as in the second example). The carriers are easily selected to be orthogonal over each subinterval.

This following explanation is provided to clarify the operation of the receiver by means of an illustrative table of values that are stored or derived in the receiver in successive bit periods.

TABLE I

In Table I the contents of FIG. 3 are repeated to show, for bits period $T_1, T_{1+5} \dots T_{1+5}$ the preceding 5 binary digits, the currently provided digit, and the 5 modulating signals.

It is assumed for illustrative purposes in this example, that $K=1$ and that the time required for modulating, transmitting, and demodulating the signals $S_1, S_2 \dots S_5$ can be ignored. Accordingly, the values stored and derived in the receiver during the corresponding bit periods $T_1, T_{1+1} \dots T_{1+5}$ are shown.

In Table I the values $Y_1, Y_2 \dots Y_5$ represents the additive noise terms that are added respectively to the modulating signals listed under $S_1, S_2 \dots S_5$, to form the output signals $W_1, W_2 \dots W_5$ of correlators $C_1, C_2 \dots C_5$. Observe that the receiver can best be understood by relating the tables in Tables I and II to the receiver diagram in FIG. 4. For example, W_1 is the sum of Y_1 and the term X_0X_1 listed under S_1 .

In Table I the values listed under $A_1, A_2 \dots A_5$ are the contents of the accumulating means $A_1, A_2 \dots A_5$ shown in FIG. 4 at the start of the bit period. Also in Table I the values listed under $X_{1r}, X_{2r} \dots X_{5r}$ are the current best estimates at the start of the bit period of the last 5 binary digits that were transmitted. Observe that X_{2r} at the start of the bit T_1 is in error. The values listed under $X_{1r}, X_{2r} \dots X_{5r}$ are stored in the digit storage stages $X_{1r}, X_{2r} \dots X_{5r}$ shown in FIG. 4 and are determined respectively by the contents of accumulating means $A_1, A_2 \dots A_5$. If the value stored in an accumulating means is negative, the corresponding digit storage stage will contain a -1 ; otherwise the digit storage stage will contain a $+1$.

The results of operations performed in the receiver during the bit period are largely shown in Table II, i.e., the results of operation performed after receipt of measurements $W_1, W_2 \dots W_5$. The first operation is to compute, using multiple 42 shown in FIG. 4, the products $W_1X_{1r}, W_2X_{2r} \dots W_5X_{5r}$. In Table II the values shown under $W_1X_{1r}, W_2X_{2r} \dots W_5X_{5r}$ are results of taking the values of $W_1, W_2 \dots W_5$ and $X_{1r}, X_{2r} \dots X_{5r}$ shown in Table I and performing the indicated multiplications.

The next operation to be performed is to sum the values $W_1X_{1r}, W_2X_{2r} \dots W_5X_{5r}$ coming out of multiplier means 42 in the summing network 44 shown in FIG. 4. The resultant sum is stored in accumulating means A_0 . This is illustrated in Table II by listing under A_0 , the sum of the values listed under $W_1X_{1r}, W_2X_{2r} \dots W_5X_{5r}$.

After the value to be stored in accumulating means A_0 has been determined the contents of digit storage stage X_{0r} are determined. If the value in A_0 is negative, a -1 is stored in X_{0r} ; otherwise a $+1$ is stored in X_{0r} . This is illustrated in Table II.

After the contents of X_{0r} have been determined, they are used to form the products $W_1X_{0r}, W_2X_{0r} \dots W_5X_{0r}$ shown in FIG. 4, using multiplying means 46. Delay means 48 shown in FIG. 4 insures that these products are not formed until the contents of X_{0r} have been determined. This operation is illustrated in Table II by showing $W_1X_{0r}, W_2X_{0r} \dots W_5X_{0r}$ to be the product of X_{0r} listed in Table II and the values $W_1, W_2 \dots W_5$ respectively that are listed in Table I.

When the products $W_1X_{0r}, W_2X_{0r} \dots W_5X_{0r}$ have been computed, they are added respectively to the contents of accumulating means $A_1, A_2 \dots A_5$. This is illustrated in Table II by showing the sum of the values under $A_1, A_2 \dots A_5$ in Table I and those under $W_1X_{0r}, W_2X_{0r} \dots W_5X_{0r}$ in Table II. For example, in Table II, the value under A_5 in bit period T_1 is the sum of the value W_5X_{0r} in bit period T_1 and the value under A_5 in Table I for bit period T_1 .

Next, the contents in digit storage stages are adjusted to indicate any change in the signs of the contents of the accumulating means $A_1, A_2 \dots A_5$. For example, the sign of A_2 is changed in bit period T_1 when W_2X_{0r} is

added. The contents of digit storage X_{2r} is accordingly changed to a +1.

The final operation is to shift the contents of $A_0, A_1 \dots A_4$ respectively into accumulating means $A_1, A_2 \dots A_5$, and similarly the contents of $X_{0r}, X_{1r} \dots X_{4r}$ into $X_{1r}, X_{2r} \dots X_{5r}$. This is illustrated in Table I and Table II by showing that the final contents of $A_0, A_1 \dots A_4$ in a bit period are respectively the starting contents of $A_1, A_2 \dots A_5$ in the subsequent bit period. Similarly the final contents of $X_{0r}, X_{1r} \dots X_{5r}$ in a bit period are the starting contents respectively of $X_{1r}, X_{2r} \dots X_{5r}$ in the subsequent bit period. The final contents of A_5 are discarded and the final contents of X_{5r} are stored as a final decision on the value of the bit transmitted 6 bit periods previously.

Although the foregoing explanation of the operation of the transmitter section of FIG. 2 and receiver section of FIG. 4 is though sufficient to fully teach an embodiment of the present invention, a more rigorous mathematical treatment is presented as follows:

Assume at first that at least n data bits have been transmitted and denote the last n bits transmitted as $X_1, X_2 \dots X_n$, indexed in the reverse order of their transmission, with X_0 the next bit to be transmitted. The data bits are assigned values ± 1 . Let the next bit period be denoted by the interval $(0, T)$ where T is the duration of the bit period in seconds or the reciprocal of the data bit rate. Let $S_1, S_2 \dots S_n$ be a set of signals (functions) which are orthonormal over the interval $(0, T)$, i.e.

$$(1) \quad \int_0^T S_i(t) S_j(t) dt = \begin{cases} 1 & \text{if } i=j \\ 0 & \text{if } i \neq j \end{cases} \quad i=1, 2 \dots n$$

The signal transmitted during the next bit period is

$$(2) \quad S(t) = KX_0 \sum_{i=1}^n X_i S_i(t) \quad 0 \leq t < T$$

where K is the transmitted amplitude factor.

At the receiver the attenuated signal is received in additive noise and has the form (neglecting the propagation time)

$$(3) \quad Z(t) = KX_0 \sum_{i=1}^n X_i S_i(t) + Y(t) \quad 0 \leq t < T$$

where $Y(t)$ denotes the additive interference and K is the received amplitude factor. Correlation of the received signal with each of the n orthonormal signals provides the basic measurements

$$(4) \quad W_i = \int_0^T Z(t) S_i(t) dt = KX_0 X_i + Y_i \quad i=1, 2 \dots n$$

where Y_i is a noise term due to the interference $Y(t)$.

Let the current decisions as to the last in data bits transmitted be denoted by $X_{1R}, X_{2R} \dots X_{nR}$. Corresponding to X_{iR} for $i=1, 2 \dots n$ is a measurement A_i which is a weighted sum of terms each of the form given by Equation 4. The manner in which these A_i are determined will become clear by following the detection process through one bit period. The values of the X_{iR} are determined by the sign of the A_i , i.e.

$$(5) \quad X_i = \begin{cases} +1 & \text{if } A_i \geq 0 \\ -1 & \text{if } A_i < 0 \end{cases} \quad i=1, 2 \dots n$$

The initial decision X_{0R} is determined from the value of

$$(6) \quad A_0 = \sum_{i=1}^n W_i X_{iR} = KX_0 G + \sum_{i=1}^n Y_i X_{iR}$$

where G is the number of correct decisions among $X_{1R}, X_{2R} \dots X_{nR}$, less the number of incorrect decisions. The decision $X_{0R}=+1$ is made if $A_0 \geq 0$; otherwise the decision is $X_{0R}=-1$.

The value of X_{0R} is now used to modify the value of A_i for $i=1, 2 \dots n$ by adding to it

$$(7) \quad X_{0R} W_i = KX_0 X_0 X_i + X_{0R} Y_i$$

Observe that $X_{0R} X_0 = +1$ if X_{0R} is correct and $X_{0R} X_0 = -1$ if X_{0R} is incorrect. If X_{0R} is correct the addition of $K X_{0R} X_0 X_i$ cause A_i to be increased if $X_i = +1$ and decreased if $X_i = -1$, i.e. if shifts A_i in the right direction for making a correct decision. If X_{0R} is incorrect the addition of $K X_{0R} X_0 X_i$ has the opposite effect, changing A_i in the wrong direction. After modifying the value of A_i , the value of E_{iR} is redetermined by equation 5 for $i=1, 2 \dots n$. The value of X_{nR} now determines the final decision as to the value of X_n . The value of A_n is discarded but the current values of $X_0, X_1 \dots X_{n-1}$ and $A_0 \dots A_{n-1}$ are retained for use and modification during the next bit period.

For transmission of the first n data bits, an n bit address vector is used in determining the reference signal. The reference for transmitting the k th data bit, $k=1, 2 \dots n$, is determined by the $k-1$ preceding data bits and $n-k+1$ bits from this address vector. The detection process is the same as though n data bits had been transmitted except that no measurements are retained for the purpose of possibly altering those bits in the reference that are from the address vector. Following each of the first n data bit transmissions one bit from the address vector leaves the reference as a "final decision."

The following information is included by way of review and to more fully describe how the received information is recovered.

Referring now to FIG. 4, observe that the first operations performed for information recovery are the n correlation operations performed in correlators $C_1, C_2 \dots C_n$. These operations are performed concurrently and are completed in one bit period. Recall that the receiver operates in synchronism with the transmitter, e.g., the requirement for bit synchronization is stated on page 3. The correlation operations are defined mathematically by Equation 4 on page 18.

As soon as the correlation operations are completed, the resulting measurements are delivered to multiplier means 42 and delay means 48. The correlators $C_1, C_2 \dots C_n$ then repeat these correlation operations over the next bit period. The following sequence of operations is also completed within the next bit period.

(a) The measurements $W_1, W_2 \dots W_n$ delivered to multiplier means 42 are multiplied respectively by the current estimates $X_{1r}, X_{2r} \dots X_{nr}$ of the last n transmitted bits. Since each of these estimates has either value +1 or -1, this amounts to no more than changing the signs of some of the measurements $W_1, W_2 \dots W_n$. Observe that this operation represents an attempt to demodulate the received signal components except for the modulation by the bit X_0 .

(b) Next, the modified measurements $W_1 X_{1r}, W_2 X_{2r} \dots W_n X_{nr}$ are summed by summing means 44 and the sum is stored as measurement A_0 . Note that the symbols $A_0, A_1 \dots A_n$ are used in the specifications to refer to both the set of measurement accumulating means and the corresponding accumulated values, but that the use of these symbols in each case is clear. Observe also that when both the demodulation attempt of operation (a) is largely successful and the level of the additive noise is comparatively low, then A_0 represents a good indicator of the state of the transmitted bit X_0 .

(c) The value of X_{0r} is determined next according to the sign of A_0 . If $A_0 \geq 0$ then $X_{0r}=+1$, and if $A_0 < 0$, then $X_{0r}=-1$.

(d) Each of the measurements $W_1, W_2 \dots W_n$ is now received from delay means 48, delivered to multiplier means 46, and multiplied by X_{0r} . As in operation (a), this amounts to at most changing the signs of some of the measurements. Observe that this operation represents an attempt to demodulate the received signal components of the bit X_0 .

(e) Next, the modified measurements $W_1 X_{0r}, W_2 X_{0r} \dots W_n X_{0r}$ are added to the measurement values $A_1, A_2 \dots A_n$, respectively. The new or resulting values

11

of $A_1, A_2 \dots A_n$ are now taken as the most reliable indicators of the values of the bits $X_1, X_2 \dots X_n$.

(f) The values of $X_{1r}, X_{2r} \dots X_{nr}$ are redetermined according to the signs of $A_1, A_2 \dots A_n$, respectively, or as follows:

$$X_{ir} = \begin{cases} +1 & \text{if } A_i \geq 0 \\ -1 & \text{otherwise} \end{cases} \quad i=1, 2 \dots n$$

(g) The value in A_n is now discarded and the values in $A_0, A_1 \dots A_{n-1}$ are shifted respectively to $A_1, A_2 \dots A_n$.

(h) The value of X_{nr} is stored as a final decision as to the value of X_n , and the values of $X_{0r}, X_{1r} \dots X_{n-1r}$ are shifted to become respectively the values of $X_{1r}, X_{2r} \dots X_{nr}$.

The above sequence of operations is repeated each bit period.

The following will provide an example of the accumulating means illustrated in FIG. 4 as $A_0, A_1 \dots A_n$.

Digital accumulating means will be described. The components of each such means consist of the following:

(a) An analog to digital converter capable of digitizing an analog value when pulsed and with the capability of holding the digital output number in preparation for a summing operation.

(b) An input digital storage unit which can accept a digital number and hold it in preparation for a summing operation.

(c) A digital summer capable of adding two stored digital numbers when pulsed, and transferring the sum to an output storage unit.

(d) An output storage unit capable of accepting and storing a digital number, and of transferring that number when pulsed to an input storage unit of the type described in (b).

Such components are well within the state of the art. The timing means necessary for maintaining bit synchronization can be readily constructed to also provide for timing or pulsing the above components so that they operate in synchronism.

The following will describe more fully how the signal is corrected in the accumulating means and reference stages $X_{0r}, X_{1r} \dots X_{nr}$.

The procedure used to determine the contents of both the accumulating means and reference stages at the end of each bit period has been described more fully previously. Observe that as measurements are accumulated, the probability of correctly estimating the transmitted bit increases, providing the signal-to-noise ratio is in excess of some minimum value. This implies that as accumulated measurements are modified and shifted through the accumulating means, some will change sign. Consequently, the corresponding estimate of the transmitted bit will be reversed. Only in this sense can errors be said to be corrected.

The following will more fully describe how the signals stored in accumulor stage A_0 are shifted through to stage A_n .

Note that after A_0 is computed, it is stored in accumulor means A_0 . At the end of the bit period, the contents are shifted into A_1 . During the next period, the contents of A_1 are modified, i.e., a "correction" term or additional measurement is added in, and at the end of that period, the contents are shifted to A_2 . This procedure of add and shift is repeated each bit period until the final contents are shifted out of A_n . Note that as these contents are modified and shifted along, they continue to refer to the same transmitted bit and, in particular, they indicate the value of that bit.

More particularly, the transfer section of FIG. 5 includes a data bit source 70 which sequentially provides bits to the first stage X_0 of a shift register illustrated as being comprised of twenty-six stages (i.e. X_0-X_{25}). The twenty-six stages of the shift register can be considered as being arranged in three groups with the first group including just one stage X_0 , the second group including

12

five stages X_1-X_5 , and the third group including twenty stages X_6-X_{25} . The stages X_0-X_{25} are interconnected such that in response to control pulses provided by a control and timing means (not shown) the content of each stage is shifted to a subsequent stage during each bit period. Bits shifted out of stage X_{25} are discarded.

The transmitter section of FIG. 5 employs a number of signal generator equal to the number of stages in the third group of the shift register. Accordingly, inasmuch as the third group of shift register stages in FIG. 5 is comprised of twenty stages, twenty signal generators S_1-S_{20} are provided. As in the embodiment of FIG. 4, the signals provided by the signal generators are preferably orthogonal with respect to one another. The input to each signal generator is derived from the output of a different one of twenty modulating gates G_2-G_{20} . The inputs to each modulating gate are uniquely connected to one stage from each of the three groups of shift register stages. Thus, for example, inputs to the gate G_8 are derived from the stage X_0 , the stage X_2 , and the stage X_{13} . Similarly, inputs to the gate G_{20} are derived from the stage X_0 , the stage X_5 , and the stage X_{25} .

In the operation of the transmitter section of FIG. 5, data bits are sequentially fed to the stage X_0 and then successively shifted through the stages X_1-X_{25} . Inasmuch as three stages controls each gate, and inasmuch as each particular bit is shifted through twenty-six stages during twenty-six successive data bit periods, each bit modulates each signal during at least three different bit periods. Accordingly, the inherent frequency and time diversity of the system should be readily appreciated inasmuch as each bit is transmitted during each of twenty-six successive bit periods to provide time diversity and over twenty different signal channels to provide frequency diversity.

The composite signal transmitted by the twenty signal generators of the transmitter section of FIG. 5 is received via conductor 89 of the receiver section of FIG. 6. The composite signal is applied to each of twenty correlators C_1-C_{20} . Also applied to each correlator is a locally generated signal, e.g. $S_{1R}-S_{20R}$ which permits each correlator to isolate a different one of the twenty signal components. The signal component isolated by the correlator C_8 can be represented by the amplitude $W_8=KX_0X_2X_{13}$ (neglecting noise). In order to ascertain from this signal the most recent data bit X_0 , previously determined reference bits X_{2R} and X_{13R} are employed.

In order to do this, as in the embodiment of FIG. 4, a plurality of reference storage stages $X_{0R}-X_{25R}$, corresponding to the twenty-six stages in the transmitter section of FIG. 5, are provided. Associated with each binary reference storage stage $X_{0R}-X_{25R}$ is an accumulating means (either analog or digital) A_0-A_{25} . As was explained in the embodiment of FIG. 4, the reference storage stages $X_{0R}-X_{25R}$ are employed to store previously determined reference data bits.

Thus, consider for example the channel in the receiving section of FIG. 6 which supplies received signal component W_8 to the multiplier 82 to which is also supplied the output of reference storage stages X_{2R} and X_{13R} . As a consequence, assuming that the previously determined reference bits X_{2R} and X_{13R} are correct, the multiplier 82 will provide an initial manifestation on its output line representing the most recent data bit, i.e. X_0 . The outputs of all of the multipliers 82 are supplied to a summing network 84 which, as in the embodiment of FIG. 4, sums all of the initial manifestations provided thereto to develop a weight which as previously explained is related to the reliability of the decision of the state of bit X_0 . That is, if all of the multipliers 82 agree on the identity of bit X_0 , then the weight determined by the summing network 84 will be at a maximum. On the other hand, if noise detracts the transmission in at least half of the channels, then the summing network 84 may develop a weight close to zero indicating a low reliability. In any event, this weight is stored in the most recent digit accumulating

means A_0 and determines the state of the reference storage stage X_{0R} . That is, as was previously mentioned, if the content of the accumulating means A_0 is positive, the state of reference storage stage X_{0R} will be forced to +1. On the other hand, if the content of accumulating means A_0 is negative, then stage X_{0R} can be forced to -1.

After a delay of $t1$ introduced by delay means 86 sufficient to assure that the most recent digit determination has been made, the identity of the most recent digit in stage X_{0R} is employed to next develop a correction manifestation with respect to one of the other digits. Thus, as is shown with respect to the signal W_8 , the output of stages X_{0R} and X_{13R} are applied to a multiplier 88 which, after a delay $t1$ introduced by delay means 86 sufficient to permit stage X_{0R} to settle, will provide a correction manifestation related to the identity of bit X_{2R} . In the specific system illustrated, it will be appreciated that four different multipliers 88 respectively associated with correlators C_5-C_8 will simultaneously provide correction manifestations to accumulating means A_2 . As long as the weight stored by accumulating means A_2 remains positive, the associated storage stage X_{2R} will define a data bit of +1, and on the other hand, if at any time the correction manifestations cause the weight to go negative, the corresponding storage stage will be forced to define a data bit of -1.

After the reference digits of the second group have been determined, they can be employed along with the most recent reference bit stored in stage X_{0R} to develop correction manifestations for the third group of reference bits. Thus, the output of stages X_{0R} and X_{2R} are provided to a multiplier 90 after a delay $t2$ introduced by delay means 92. Multiplier 90 will provide a correction manifestation to the corresponding accumulating means. Thus, the multiplier 90 associated with the correlator C_8 will correct the weight in accumulating means A_{13} which of course controls the state of the storage stage X_{13R} . After correction manifestations have been provided to the second and third groups of reference storage stages, the weights stored in the accumulating means A_0-A_{24} are shifted to 40 a subsequent accumulating means. The weight stored in accumulating means A_{25} is discarded. The data bit stored in reference storage stage X_{25R} is stored as a final decision. Thereafter, the receiver section of FIG. 6 is then ready to receive a new data bit during a subsequent bit 45 period.

In addition to the foregoing, embodiments of the invention inherently possess an adaptive capability which has not thus far been stressed. This capability may prove useful in the acquisition of a transmitted signal. Briefly, suppose the receiver is turned on so that the sequence of receiver operations such as correlations, decision making, combining correlation measurements, shifting, etc., is initiated. Note that normally measurements in accumulating means A_1-A_n represent a type of bias or what might be considered an indication of the proper reference. Suppose that all such bias is removed and the receiver is not otherwise disposed to expect a fixed signal (initial reference) before starting to accumulate measurements in A_1-A_n . If then a proper signal (receiver is designed to match the transmitter) is being transmitted, the receiver will be operating on this signal, making decisions, and accumulating measurements. At any point, either of two cases will usually exist; either there will be more than half, or less than half, of the current decisions $X_{1R}-X_{nR}$ in error. In either case, the measurements accumulated will tend to reinforce the decision and sustain that case. For example, if initially more than half of the reference decisions $X_{1R}-X_{nR}$ were correct, and supposing the signal to noise ratio is large enough to sustain reliable communication, the decision X_{0R} would tend to be correct, and if so, would provide the proper correction manifestations to A_1-A_n to improve the reference by reducing the numbers of errors. Note at this point the measurements in A_1-A_n would be of small magnitude so that sign changes could be readily

accomplished. As the number of errors in $X_{1R}-X_{nR}$ is reduced, the probability of making the decision X_{0R} correctly is increased. Thus, the receiver tends to adapt its reference to the transmitted signal. This is true in either case. In the case where initially more than half of $X_{1R}-X_{nR}$ were incorrect, the receiver will tend to adjust the reference to the negative or mirror image of the correct reference, and it is only necessary to recognize this fact in interpreting final decisions.

From the foregoing, it should be appreciated that a system has been disclosed herein suitable for transmitting and receiving binary data. As pointed out, the system is based on the concept of transmitting a future reference for facilitating data bit recovery at the receiver. Because of the inherent time and frequency diversity of the system and the m -fold modulation, lower signal to noise ratios can be tolerated before any data is lost. Alternatively, the system enables users to transmit at lower power levels than required by other systems for similar signal to noise ratios.

What is claimed is:

1. A system for transmitting an ordered sequence of binary digits 0, 1, 2 . . . n wherein said digits n and 0 are respectively earliest and latest in said sequence, said 25 system including:

n signal generators;

means responsive to each of said digits 1, 2 . . . n for modulating a different one of said signal generators; and

means responsive to said digit 0 for modulating all of said signal generators.

2. The system of claim 1 wherein each of said n signal generators provides a signal orthogonal to the signal provided by each of said other signal generators.

3. In combination:

a source providing a sequence of binary digits; n generators each providing a unique signal; means for individually modulating said n generators; and

each of said digits in sequence starting with a specified starting digit simultaneously modulating all of said n generators for a single bit period;

each of said digits beginning with said starting digit subsequently modulating each of said n generators in sequence for one bit period starting with the first generator.

4. The combination of claim 3 wherein said signals provided by said n generators are all orthogonal to one another.

5. The combination of claim 3 wherein said means for developing said set of n modulating signals includes a shift register having $n+1$ stages;

means initially providing said binary digits to a first of said $n+1$ shift register stages; n gates; and

means coupling said first shift register stage to all of said gates and each of said other shift register stages to a different one of said gates.

6. The combination of claim 3 including means for demodulating said n modulated signals, said means for demodulating including means for continually developing a sequence of n reference binary digits intended to correspond to said n previously provided binary digits.

7. The combination of claim 6 wherein said means for developing said sequence of reference digits includes n reference storage stages each capable of storing one of said reference digits, and means responsive to each of said reference storage stage for demodulating the one of said n modulated signals corresponding thereto for developing n initial manifestations each intended to represent said most recently provided binary digit.

8. The combination of claim 7 including a most recent digit accumulating means for developing a sum of said initial manifestations to determine said most recently pro-

vided binary digit and a most recent digit storage stage responsive to said most recent digit accumulating means.

9. The combination of claim 8 including means responsive to said most recent digit storage stage and each of said n modulated signals for developing n correction manifestations each intended to represent a different one of said n previously provided binary digits.

10. The combination of claim 9 including n accumulating means each coupled to a different one of said n reference storage stages for controlling the state thereof; and means applying each of said n correction manifestations to a different one of said n accumulating means.

11. The combination of claim 10 including means for shifting the contents of said most recent digit accumulating means to a first of said n accumulating means and for shifting the contents of each of said n accumulating means to a subsequent one of said n accumulating means.

12. In a digital data communication system:
a source of successive binary digits;
at least first and second groups each comprised of one or more binary stages;
means successively applying said binary digits to a first of said stages;
means for shifting the contents of each of said stages, other than a last stage thereof, to an immediately succeeding stage between the successive application of binary digits to said first stage; 25
a plurality of generators each providing a unique signal;
a plurality of modulator means, each responsive to one stage from each of said groups; and
means coupling each of said modulator means to a different one of said generators for modulating the signal provided thereby.

13. The system of claim 12 wherein said first group consists only of said first stage.

14. The system of claim 12 wherein said signals provided by said generators are orthogonal to one another.

15. In a digital communication system for transmitting and receiving a sequence of binary digits provided by a data source;

means for storing in order the last n binary digits provided by said source;
 n generators each providing a unique signal; and
 n modulator means each responsive to a different one of said last n binary digits and the next binary digit provided by said source for modulating a different one of said n generators.

16. In a digital communication system for transmitting and receiving a sequence of binary digits provided by a data source;

means for storing in order the last p binary digits provided by said source;
 $n(n \leq p)$ generators each providing a unique signal; and
 n modulator means each responsive to a unique combination of one or more of said last p binary digits and the next binary digit provided by said source for modulating the signal provided by a different one of said n generators.

17. The system of claim 16 including means for demodulating said signals comprising means for developing a sequence of p reference binary digits;
means for employing each of said p reference binary digits to develop each of said unique combinations; and
means responsive to each of said unique combinations and said modulated signals for ascertaining said next binary digit provided.

18. The system of claim 17 including means responsive to said ascertained next binary digit for developing said sequence of reference digits.
